UNITED STATES PATENT OFFICE

BERT O. TILDEN, OF TRENTON, NEW JERSEY, ASSIGNOR TO B. O. T. MANUFACTURING COMPANY, OF TRENTON, NEW JERSEY, A CORPORATION OF NEW JERSEY

DESIGN FOR AN INTEGRAL WATER CLOSET COMBINATION

Application filed December 26, 1931. Serial No. 42,203. Term of patent 14 years.

To all whom it may concern:

Be it known that I, BERT O. TILDEN, a citizen of the United States, residing at Trenton, in the county of Mercer and State of New Jersey, have invented a new, original, and ornamental Design for an Integral Water Closet Combination, of which the following is a specification, reference being made to the accompanying drawings, forming a part thereof.

Figure 1 is a side elevation of the article, showing my new design; Fig. 2 is a front elevation, Fig. 3 is a top plan and Fig. 4 is a perspective.

I claim:

The ornamental design for an integral water closet combination, as shown.

BERT O. TILDEN.
